RESPIRATOR LOCKING MEANS

Willis Z. Whipple, Chicago, Ill., assignor to Chicago Eye Shield Company, Chicago, Ill., a corporation of Illinois

Application December 22, 1943, Serial No. 515,321

4 Claims. (Cl. 128—146)

The present invention relates to respirators and, more particularly, to an industrial respirator having a novel locking means adapted to hold readily removable filter boxes to the face piece of such a respirator in a fixed and immovable position during use of the respirator.

A principal object of the invention is the provision of a respirator comprising a face piece having gripping means thereon and a removable filter box having receiving means on one of its walls connected to the gripping means, and a novel locking means cooperatively associated with the gripping and receiving means to hold the filter box in fixed and immovable position on the face piece of the respirator during use.

More specifically, it is an object of the invention to provide an industrial respirator having a face piece with an air inlet and gripping means around the inlet, and a removable filter box with spaced apart resilient walls having receiving means on one of the walls connected to the gripping means around the inlet to draw the parts firmly together, the gripping means having a link extending therefrom which is connected to a projection on a wall of the filter box, and a novel locking member, secured to a head strap, mounted on the projection to hold the filter box in fixed immovable position to the face piece when the head strap is secured in position for using the respirator.

Other objects of the invention will in part be obvious and will in part appear hereinafter.

The invention accordingly comprises an article of manufacture possessing the features, properties, and the relation of elements which will be exemplified in the article hereinafter described and the scope of the application of which will be indicated in the claims.

For a fuller understanding of the nature and objects of the invention reference should be had to the following detailed description taken in connection with the accompanying drawing, in which:

Fig. 1 is a rear elevational view of a respirator embodying the invention;

Fig. 2 is a plan view of a filter box about to be locked into fixed and immovable position;

Fig. 3 is a view similar to Fig. 2 illustrating the filter box in locked and immovable position;

Fig. 4 is a transverse view, partly in section, of a fragmentary portion taken along the line 4—4 of Fig. 3 and looking in the direction of the arrows; and

Fig. 5 is a transverse view, partly in section, of a fragmentary portion taken along the line 5—5

of Fig. 3 and looking in the direction of the arrows.

Referring more particularly to the drawing, there is shown a face piece 10 with filter boxes 11 mounted thereon. The type of industrial respirator herein used for illustrative purposes is that described in detail in Patent No. 2,295,119 of which I am a co-inventor. There are certain details of that patent not illustrated herein but they do not particularly deal with the presently claimed invention which, briefly, is concerned largely with locking face pieces to filter boxes in fixed and immovable position by means of a novel type of locking device associated therewith, after the filter boxes have been mounted in position.

The respirator has a plurality of filter boxes but since they are substantially identical, and since one of such boxes alone could be used in practicing the present invention, it is deemed sufficient to describe only one of them.

The filter box 11 is secured to the face piece 10 by any suitable type of gripping means, such as a bayonet joint, or other conventional snap-on arrangement whereby the wall section of the filter box which is adjacent the face piece is firmly and securely drawn or pressed to the face piece to prevent leakage.

The particular gripping means used herein is indicated generally at 12 and consists of a grommet or flanged member 13 attached to the face piece 10. Attached inside the wall of a filter box is a receiving means 14 or ring with lugs 15 for receiving gripping elements 16 which are adapted to cooperate securely to clamp the wall of the filter box against the flange 14 around an air inlet indicated at 17.

On the inside of the filter pad, which preferably consists of spaced apart resilient walls, an extension 18 is connected to the receiving means 14 and this terminates in a stud 19 which projects through the wall of the filter pad. This stud, where it penetrates the pad, is sealed against leakage by a washer 20. The stud terminates in a head 21 and has an annular groove 22 below the head.

Extending from the gripping means or flange 13 is a link or arm 23 which terminates in a slotted enlargement or hook 24. In assembling the filter box, the gripping means attached to the face piece 10 is inserted within the receiving means 14 and given a slight turn to preliminarily lock the filter box to the face piece at this point, the arrangement of the parts of the gripping means and the receiving means being such that the filter box will be secured in its most

convenient position for use. During this securing operation the extension arm 23 terminating in the hook 24 becomes secured in position around the stud 21, the stud coming to rest against a shoulder 25 of a slot 26 in the hook 24.

Also mounted upon the stud 21 is a T-slotted member 27. One slot of the T has secured therein a head or neck strap 28. The other slot of the T rides in the annular groove 22 of the stud 21 and the entire T-slotted member overlies the hook 24 on the extension 23. Projecting from one leg of the T-slotted member is a U-shaped hook 29 which constitutes an important portion of the locking means.

As the filter box is swung into fitted position so that the stud 21 enters the slot 26 of the hook, a portion 30 of the hook 24 enters the U-shaped hook 29. The filter pad is now located in its intended position and when the head strap is swung into position, the T-slotted member 19 pivots around the stud 27 with the U-shaped hooked member 29 swinging around the portion 30 of the edge of the hook member 24, locking the connected parts securely together and holding the filter box in fixed and immovable position during the time the respirator is in use (Fig. 3).

It is very desirable that the filter boxes be quickly removable so that they can be cleaned and sterilized from time to time during the period of a working day if necessary. This is readily accomplished when the head or neck strap is removed by the wearer, because in doing so, the locking members automatically disengage themselves and the filter box can readily be removed from its seated position against the face piece.

It will thus be seen that the objects hereinbefore set forth can readily and efficiently be attained and since certain changes may be made in the above article and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the

invention which, as a matter of language, might be said to fall therebetween.

Having described my invention, what I claim as new and desire to secure by Letters Patent is:

- 5 1. In an industrial respirator, the combination comprising a face piece with gripping means thereon, a removable filter box with spaced apart walls having receiving means on one of said walls connected to said gripping means, said gripping means including a link removably connected to a projection on a wall of said box, and a locking member securing said link to said projection and holding said box in fixed immovable position on said face during use of said respirator.
- 10 2. In an industrial respirator, the combination comprising a face piece having gripping means thereon, a removable filter box having receiving means on one of said walls connected to said gripping means, said gripping means including a link removably connected to a projection on a wall of said box, said projection being connected with said receiving means, and a locking member securing said link to said projection and holding said box in fixed immovable position on said face piece during use of said respirator.
- 15 3. In an industrial respirator, the combination comprising a face piece having gripping means thereon, a removable filter box with spaced apart walls having receiving means on one of said walls connected to said gripping means, said gripping means including a link removably connected to a projection on a wall of said box, and a locking member carrying a head strap, mounted on said projection and holding said box in fixed immovable position to said face piece when said head strap is secured in position for use of said respirator.
- 20 4. In an industrial respirator having a demountable filter box held to a face piece by securing means, the improvement comprising a link having a hooking member, said link being connected to said securing means, said hook engaging a projection on a wall of said box, and locking means, carrying a head strap, mounted on said projection, said locking means holding said hooking member against said projection and securing said box in fixed immovable position during use of the respirator when the head strap is in position.

convenient position for use. During this securing operation the extension arm 23 terminating in the hook 24 becomes secured in position around the stud 21, the stud coming to rest against a shoulder 25 of a slot 26 in the hook 24.

Also mounted upon the stud 21 is a T-slotted member 27. One slot of the T has secured therein a head or neck strap 28. The other slot of the T rides in the annular groove 22 of the stud 21 and the entire T-slotted member overlies the hook 24 on the extension 23. Projecting from one leg of the T-slotted member is a U-shaped hook 29 which constitutes an important portion of the locking means.

As the filter box is swung into fitted position so that the stud 21 enters the slot 26 of the hook, a portion 30 of the hook 24 enters the U-shaped hook 29. The filter pad is now located in its intended position and when the head strap is swung into position, the T-slotted member 19 pivots around the stud 27 with the U-shaped hooked member 29 swinging around the portion 30 of the edge of the hook member 24, locking the connected parts securely together and holding the filter box in fixed and immovable position during the time the respirator is in use (Fig. 3).

It is very desirable that the filter boxes be quickly removable so that they can be cleaned and sterilized from time to time during the period of a working day if necessary. This is readily accomplished when the head or neck strap is removed by the wearer, because in doing so, the locking members automatically disengage themselves and the filter box can readily be removed from its seated position against the face piece.

It will thus be seen that the objects hereinbefore set forth can readily and efficiently be attained and since certain changes may be made in the above article and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the

invention which, as a matter of language, might be said to fall therebetween.

Having described my invention, what I claim as new and desire to secure by Letters Patent is:
